UNITED STATES PATENT OFFICE.

DONALD J. CAMPBELL, OF MUSKEGON HEIGHTS, MICHIGAN.

MOLDING APPARATUS.

Application filed February 4, 1925, Serial No. 6,728. Renewed August 20, 1928.

This invention relates to molding apparatus with which green sand molds may be formed around patterns in flasks. In making molds of the character stated, it is necessary to pack or condense the sand to a certain degree and with the apparatus of my invention, such condensing and packing or tamping effect is accomplished by vibrating the flask, pattern and sand in the flask, also the table which carries the same with the effect of condensing the sand in the lower portion of the flask. To condense the sand in the upper portion of the flask, a sand squeezing operation is performed, either after the vibrating operation or simultaneous therewith, this latter operation being preferred in many instances in order that the sand shall not be loose and fluffy in the upper part of the flask, as may be the case where vibration only takes place. My invention includes means for vibrating the sand through an electrically operated agency, rapid and relatively light vibrating raps being given to the supporting table carrying the flask, pattern and sand, and this electrically operated means is operable both while the squeezing operation is taking place and when not taking place.

My invention has for its primary object and purpose, the construction of a molding apparatus, and one which is very practical and effective, for performing the vibrating and squeezing operations stated, either at different times or simultaneously, the vibration being effected through electrically operated means. A further object of the invention is to construct an apparatus of the character outlined, wherein the vibration may be started at will and stopped after a predetermined number of vibrations have taken place through an automatic control therefor. Many other objects and purposes than those stated, all directed to the production of a relatively simple, durable and practical machine of the kind stated, will appear as understanding of the invention is had from the following description, taken in connection with the accompanying drawings, in which,

Fig. 1 is a front elevation of the molding apparatus made in accordance with my invention, the flask being shown in vertical section.

Fig. 2 is a horizontal section therethrough at a plane below the flask holding table. 55

Fig. 3 is a fragmentary horizontal section through the compressed air control used for cooling the electrical elements and for the squeezing operation.

Fig. 4 is a fragmentary enlarged vertical 60 section taken substantially on the plane of the broken line 4—4, of Fig. 2.

Fig. 5 is a vertical section taken centrally of the machine on a plane substantially at right angles to the plane of the section shown 65 in Fig. 4, the apparatus being in lower position.

Fig. 6 is a view similar to that shown in Fig. 5, with the apparatus in upper squeezing position. 70

Fig. 7 is a diagrammatic view of the electric circuits controlling the electric vibrating means, the automatic circuit breaking mechanism for stopping the vibration after a predetermined number of vibrations being shown 75 in side elevation, and

Fig. 8 is a perspective view of the rotary commutator used for controlling the circuits to the two solenoids which operate the vibrating element of the apparatus. 80

Like reference characters refer to like parts in the different figures of the drawings.

In the construction of the molding apparatus, a lower casting is provided having a base 1 from which a large vertical cylinder 85 2 extends upwardly between the ends of the base. The base at the lower end of the cylinder is arched into substantially semi-spherical form, as indicated at 3 and reinforced and strengthened by such form as well as by 90 strengthening ribs located below the part 3. At a number of points around the cylinder 2, four of such places being shown, lugs 4 extend outwardly on each of which a pin or rod 5 is fixed and extends upwardly therefrom. 95 A strong coiled spring 6 is located around each pin 5, resting at its lower end on its lug 4 and extending at its upper end above the rod 5. Two other lugs 7 are also cast with the cylinder 2 and extend outwardly 100 therefrom at diametrically opposed points, each having an opening therethrough suitably bushed, the purpose of which will later appear. Two smaller vertical cylinders 8 are also cast with the base 1, being located 105 at opposite sides of the cylinder 2 and in aline-

ment with the lugs 7. Vertical ribs 9 are disposed between the cylinders 2 and 8, the same extending nearly to the upper ends of said cylinders for purposes of reinforcing the structure.

A piston or plunger ram 10 is mounted vertically within the large cylinder 2, at its upper end extending a short distance above the upper end of the cylinder and adjacent to its lower end being provided with rings to prevent the escape of compressed air upwardly between the sides of the piston and walls of the cylinder. The piston or ram is hollow, having an open upper end and an integrally cast lower end 11 shaped to correspond with the bottom 3 of the base directly below. A short distance above the bottom 11 an integral horizontal partition plate 12 is located, the central portion of which is supported on an integral upper extension to the bottom 11, there being enclosed between the bottom 11, partition 12 and said central support, an annular recess or chamber 13. A relatively heavy block 14 of metal is carried at the upper side of the partition 12, being of substantially cylindrical form and projecting above the partition, as shown.

A plurality of vertical openings 15 are made through the partition 12 near the walls of the piston or ram 10. Near the upper end of the piston an annular integral and inwardly extending rib or ledge 16 is made between which and the partition 12 a plurality of vertical and radially positioned ribs or vanes 17 are located being cast with the piston. A number of spaced openings 18 are made through each part 17.

In the upper end of the piston 10 and resting on the ledge 16 is a plate 19 formed at its central portion with a downwardly extending cylindrical boss, 19^a located directly above the block 14. Both the boss 19^a and the block 14 may be hardened in order to withstand the striking of the vibratory body designed to move back and forth between them. A cylindrical sleeve 20 is disposed between block 14 and the boss 19^a, its ends receiving said block and boss as shown. A body 21 of cylindrical form is located within the sleeve 20 and its smaller projecting ends may also be hardened. Upper and lower solenoid windings 22 and 23 are located around the upper and lower ends of the central sleeve 20, being separated at their adjacent ends by a ring 24 of suitable insulating material. It is evident that with alternate energizing of the solenoids, the vibrating body will be elevated and dropped, striking the boss 19^a and the block 14 alternately.

At the upper end of the piston 10 and above the plate 19, a circular plate 25 is located completely closing the open upper end of the piston. A vertical support 26 integral with the plate 25 at its upper end carries a table 27 on which the pattern is to be carried.

At points directly over the lugs 7, downwardly extending bosses 28 are formed on the table 27, the same being recessed at their upper sides, as indicated at 29. Rods 30 formed at their lower ends with heads 31 pass upwardly through the bushings in the openings in lugs 7 and through the bosses 28, being secured in place by nuts received in the recesses 29. In addition, other bosses 32 are cast with the table 27 and extend downwardly therefrom, one for each spring 6, being adapted to engage against the upper ends of said springs when the piston and table are in lower position, as shown in Fig. 4.

A pattern board 33 is adapted to bear against the upper side of the table 27 on which the pattern 34 may be carried. A stripping plate 35 formed with downwardly extending flanges 36 at its sides is located over the table 27, resting thereon normally, the stripper plate having an opening in which the pattern board is received and having its upper side flush therewith. The flask 37 placed around the pattern is carried on the stripper plate and detachably held thereon, suitable pins 38 on the stripper plate, as shown in Fig. 4, passing through openings in the out-turned flanges of the flask. The stripper plate is formed with two downwardly extending bosses 39 to each of which a cylinder 40 is connected, one of these cylinders being located in each of the cylinders 8, previously described. It is evident that when air is entered into the lower end of the cylinders 8, the stripper plate may be elevated or after elevation held in elevated position, while the piston 10 being allowed to drop, the pattern will be drawn from the mold. Outlet openings are made through the ledge 16 and plates 19 and 25 through which short lengths of pipe 41 may be passed, serving as exhaust passages for air circulated within the piston 10 around the solenoids, as will hereafter appear.

At the outer side of each cylinder 8 a vertical support 42 is secured, extending above the upper end of its adjacent cylinder 8 and divided at such upper end to make spaced apart ears 43. A rod 44 is pivotally connected at 45 at its lower end to and between each of the pairs of ears 43. These rods extend upwardly and are threaded at their upper portions. A beam 46 is located between the two rods (see Fig. 1), said rods passing through the ends of the beam, and nuts 47 on the rods, one above and the other below the beam are used to adjustably secure the beam on said rods. A squeezing head adapted to fit into the upper end of the flask 37 is carried by and under the beam directly over said flask, this head being indicated at 48.

The squeezing head thus mounted and supported is adapted to be moved into position so as to stand directly over the flask and may also be moved out of the way to one side so

that sand may be placed in the flask in filling the same. Adjustable stops 49 are carried at each side of the supports 42 against which outwardly extending projections at 5 the lower ends of the rods 44 may engage to limit the extent of movement of the squeezing head.

The piston or ram 10 is designed to be elevated in the cylinder 2 by compressed air 10 introduced into the lower end of the cylinder under the piston. At the front side of the apparatus, a post 50 (see Fig. 1) is located, at the upper end of which a valve casing 51 is carried formed with a longitudinal passage 52 therethrough and at each end of which a valve 53 is rotatably mounted. Compressed air is carried to said passage through a pipe 54 (see Fig. 3). A pipe 55 leads from a side of the casing 51 at one end thereof adjacent where one of the valves 53 is mounted, and at its opposite end is connected with the lower end of the cylinder 2 (see Figs. 5 and 6). When the valve is turned to one position air may be carried through the conduit 55 to the cylinder under the piston 10 which is elevated, as is obvious. The extent of elevation is limited by the heads 31 of rods 30 engaging against the under sides of the lugs 7. A flexible hose conduit 56 leads 30 from the end of the casing 51 to the upper portion of the piston 10 and thence has a branch pipe 57 which extends downward through the horizontal partition 12 into the chamber 13. By turning the valve 53 to another position, air can be directed through this conduit to the chamber 13 from which it escapes through the openings 15 and 18 to the outlets 41, serving to cool the solenoids when needed. In the position of the valve, 40 shown in Fig. 3, the air is cut off from escape from the casing 51 to either conduit. The valves 53 are manually operated by means of handles 53^a located above the casing 51 and connected with the valves.

45 The valve at the right hand end of the casing 51, shown in Fig. 2 as operable by means of a handle 53^b may be operated to direct compressed air through the pipe 58 to operate the squeezing head to operative position, as shown in my pending application, Ser. No. 3,313, filed Jan. 19, 1925, or to control the passage of air to the cylinders 8 under the pistons 40 when this is desired in drawing the pattern from the mold.

55 A wire 59 connects with one end of the upper solenoid winding 22 and a wire 60 with one end of the winding for the lower solenoid 23. The other ends of the two windings are connected by a wire 61 with which 60 a wire 62 of an electric circuit is connected, the same being the feed wire carrying the current to the solenoids. A third solenoid 63 is housed in a suitable casing 64, one end of the winding being connected by wire 65 65 with the wire 60, and the other by wire 65^a

with the wire 62. The two wires 59 and 60 lead to two spaced apart brushes 66 and 67, which with two other spaced apart brushes 66^a and 67^a are located so as to have their free ends contact with a drum 68 mounted 70 for rotation on the shaft of an electric motor. This drum carries two metal bands 69 and 70 spaced from each other substantially the same distance apart as are the brushes 66 and 67 and 66^a and 67^a. Each of these bands extends 75 one half the way around the drum and one begins where the other ends, as shown. In this manner two brushes 66 and 66^a or the two brushes 67 and 67^a are in electrical connection, but only two of them at a time. 80 And such electrical connection takes place alternately with the rotation of the drum, such alternate connection occurring with great rapidity, dependent upon the rotation of the drum 68.

85 A ground wire 71 is connected with the brush 67^a and has a branch wire 72 connected with the brush 66^a. A manually operable switch is interposed in the length of the wire 62 operation of which will close a 90 circuit for the energizing of the solenoids 22 and 23 alternately, resulting in the alternate elevation and dropping of the vibrating body 21. The circuit is through wire 62, solenoid winding 22, wire 59, brush 66^a, band 70, contact brush 67^a and wires 72 and 71 when the brushes 66 and 66^a are in contact engagement with the band 70; and it is through wire 62, solenoid winding 23, wire 60, brush 67, band 69, brush 67^a and wire 71 when the band 69 100 is in position to connect the brushes 67 and 67^a. Accordingly, there is alternate energizing of the two solenoids with a consequent attraction of the vibrating body acting as the core of the solenoids and moved by 105 them.

110 The solenoid 63 is energized whenever the lower solenoid 23 is, a part of the current being shunted from the wire 62 through wire 65^a, through the winding 63 and thence through wire 65 to the wire 60. As a result, the core 76 attracted by said solenoid 63 is elevated with each elevation and dropping of the vibratory body 21. This is for the purpose of operating an automatic control for 115 the vibratory body to stop vibration of the same after a predetermined number of complete vibrations. If the switch 73 was closed and held closed, being released when the vibration had continued long enough, such 120 automatic control would not be needed. However, the control of the switch 73 in such case would be dependent upon the operator and it is more satisfactory to have such control automatic. The construction for effecting this will now be described.

125 A supporting bracket 74 (see Fig. 7) is provided, at one end being formed with an upwardly extending post 75 located directly under the rod 76 which extends into the 130

winding of the solenoid 63, providing the attracted core therefor. An arm 77 is pivotally mounted at one end on a stud 78 carried by the bracket and adjacent its end is connected to the rod 76 near its lower end. A spring 79 disposed between the free end of the arm 77 and the bracket 74 normally tends to hold the rod 76 in lower position. A ratchet wheel 80 is rotatably mounted on the stud 78 engaging with which is one pawl 81 carried on the rod 76, and a second pawl 82 pivotally mounted on the bracket 74 at the opposite side of the ratchet wheel. It is evident that with each reciprocation of the rod 76, wheel 80 is moved one step, the pawl 81 passing from one tooth to the next.

A pin 83 projects outwardly from the ratchet wheel 80 near one edge thereof and is at times adapted to engage with a lever 84 pivotally mounted between its ends on the bracket 74 and spring actuated to normally turn the lever in a clockwise direction about its pivot. The outer end of the lever carries a binding post and contact 85 suitably insulated from the lever. The bracket 74 carries a second contact and binding post 86 directly below the post 85. A wire 87 connects post 85 with the wire 62 and a wire 88 connects the other post 86 with said wire, the manually operated switch 73 being interposed in wire 62 in the length thereof between the points of connection of wires 87 and 88 thereto. It is evident that as soon as the pin 83 is moved beyond the end of the lever 84, contacts 85 and 86 press together and the circuit normally broken by the switch 73 is closed. As a result, the operator in starting the apparatus in operation by pressing the switch 73 inward, has to hold said switch closed but a very short time or until the reciprocation of the rod 76 has, through the pawl 81, moved the ratchet wheel far enough that pin 83 has moved out of the range of the lever 84, whereupon the circuit is closed by engagement of contacts 85 and 86 and the operator may release switch 73.

The reciprocation of the rod 76 continues with a corresponding vibration of the body 21 until the pin 83 has moved in a circle to again engage the end of the lever 84, this moving the contacts 85 and 86 apart, breaking the circuit, and stopping the vibration automatically until again started by closing the switch at 73. The number of vibrations is dependent upon the number of ratchet teeth in the wheel 80 and this can be varied different sizes of wheels being adapted to be used as it is evident that the pin 83 may be positioned differently on different wheels and the pawls 81 and 82 changed if necessary to correspond with a different wheel.

It will be noted that wires 59^a, 60^a and 62^a lead from the wires 59, 60 and 62, respectively, as shown in the diagram of wiring shown in Fig. 7. This is to illustrate the possibility

of operating more than one, in fact as many machines as may be desired with the use of but one commutator and motor for driving the same. For a second machine, the wire 62^a is the feed wire, and wires 59^a and 60^a serve the same functions and are connected with the second machine in the same manner as wires 59 and 60 are connected in the apparatus shown. This system of wiring may be indefinitely repeated for as many machines as may be in use.

The mechanism comprising the solenoid 63 and the automatic stop mechanism may be housed in any suitable housing, such as 89 and mounted at a side of the cylinder 2, the switch 73 extending outwardly through an opening in the housing so as to be accessible for operation. Of course, this housing with its contained mechanism need not be mounted at any particular place as it will operate wherever placed if properly connected, but the place shown is one very convenient. The wiring is indicated at C, as a cable and the wires 59, 60 and 62 are carried to the solenoid located within the piston or ram 10 through a suitable insulating block 90. The cable C, as shown in Figs. 1 and 5 is long enough that the piston may have its full travel, and it is evident that the vibration of the body 21 may take place whatever the position of the part 10, either when in lower or upper position, or during the time it is moving between such extreme positions.

With the flask filled with sand over the pattern, and with the piston 10 and the table and flask carried thereby in lower position, as shown in Figs. 1, 4 and 5, the vibrating and squeezing of the sand may be done, either separately or simultaneously. For instance, in order that the sand in the upper part of the flask shall not be loose and free to jump upwardly under the vibration caused by the striking of the body 21 against the parts 14 and 19, it is advisable in some classes of work to elevate the flask to the position shown in Fig. 6 and bring the squeezing head 48 against the upper part of the sand before the vibration is started. In such case valve 53 is operated to pass compressed air into the lower end of the cylinder 2, elevating the flask to upper position after which the switch 73 may be momentarily closed and the cycle of vibrations gone through. The body 21 vibrating back and forth between the parts 14 and 19, strikes both parts with considerable force, thereby vibrating the table and flask and condensing the sand under the squeezing head. Another manner in which the apparatus may be used is to start the vibration when the mechanism is in lower position, and elevate it during the time of vibration and this may be done so that the elevation is completed before the vibration stops, or the vibration may be stopped before the elevation is complete; or, as is evident,

the vibration may be carried through before the elevation is begun. The apparatus may be operated in any of the ways stated as seems best in the particular circumstances.

6 While an upper and lower solenoid 22 and 23 are shown, it is evident that my invention is workable with an elimination of the lower solenoid, the vibrating body being allowed to fall by gravity, and being lifted by the upper 10 solenoid. While not as satisfactory and not as complete an apparatus as that shown, my invention is capable of embodiment in such manner.

After the mold is complete, having been 15 vibrated and squeezed and positioned as shown in Fig. 6, air may be entered into the cylinders 8 to hold the stripping plate with the flask and mold in upper position. The air may be exhausted from the cylinder 2, 20 passing through the conduits 55 and 56 when the valve 53 is in the position shown in Fig. 3, the solenoids being thus cooled after each vibration cycle. The lowering of the table and pattern following from such exhaust of 25 air from the cylinder 2, with the stripping plate and flask and mold held in upper position, draws the pattern from the mold. If the return of the piston or ram 10 and attached table is too rapid, no detrimental 30 effects occur, the springs 6 softening and absorbing the shock. These springs may also have a further function when the vibrating takes place with the parts in lower position, yielding slightly on the downward movement 35 of the vibrating body and softening any possible destructive striking of the body against the lower member 14. These parts 14 and 19^a, preferably of hardened material may be hardened to a greater or less extent, as may 40 be needed, so as to soften the vibrations in either direction if, for different reasons, this seems advisable.

The construction described is simple and effective for the production of molds from 45 green sand. Many changes in specific structural detail may be resorted to without departing from the invention defined in the appended claims, and the invention is to be considered as comprehensive of all such modifications or changes that come within the 50 scope of said claims.

I claim:

1. In molding apparatus, a vertical support, a table at the upper end of the support 55 on which a pattern and a flask around the pattern may be carried, an annular solenoid winding fixed to said support and a vibrating body surrounded by said winding and adapted to be raised when the winding is energized 60 and dropped when the winding is de-energized, the said body striking the said support at each extreme of its movement.

2. In molding apparatus, a vertical support, a table located at the upper end of the 65 support, a vibrating body mounted within the

support and adapted to reciprocate therein, upper and lower solenoid windings located within the support around said body, and means to alternately energize said windings whereby the body is alternately elevated and 70 dropped, substantially as and for the purposes described.

3. In molding apparatus of the class described, a vertical hollow support, a plate 75 closing the upper end of the support, means extending across the lower portion of the support including a block, said plate having a depending boss in alignment with said block, upper and lower solenoid windings located one over the other between said block and 80 boss, a vibrating body located within the solenoids between the block and boss, and means to alternately energize the solenoids, substantially as and for the purposes described. 85

4. In molding apparatus of the class described, a vertical support, a sleeve mounted vertically within said support, a hardened block extending into the lower end of the sleeve, a plate having a depending hardened 90 boss at the upper end of the sleeve, said boss extending into said end of the sleeve, a table carried at the upper end of the support and resting on said plate, a solenoid winding around the upper end of the sleeve, a vibrating body loosely mounted within said sleeve between said block and boss, and means to periodically energize said solenoid winding, substantially as and for the purposes described. 95

5. A construction containing the elements in combination defined in claim 4 combined with means for circulating air within said support around said solenoid winding, substantially as described. 100

6. In molding apparatus of the class described, a vertical support, a sleeve positioned vertically within the support, hardened members at the upper and lower ends of said sleeves, a table carried at the upper end of the support and contacting with the upper hardened member, a vibrating body loosely mounted in the sleeve between said members, and electric means for moving said vibrating body back and forth in the sleeve whereby the 110 same strikes against said members at the ends of its movements in the sleeve thereby vibrating the table, substantially as described. 115

7. In combination, a table adapted to carry a pattern and a flask around the pattern, a 120 sleeve located vertically under the table, a vibrating body mounted in the sleeve and adapted to move back and forth in the same, and electric means around the sleeve at each end thereof for alternately attracting said body to thereby reciprocate the same, substantially as described. 125

8. In combination, a base, a relatively large cylinder extending upwardly from the base, a piston or ram mounted in the cylinder for 130

vertical movements, a table carried at the upper end of the piston, a vertical sleeve located within the piston, the upper end of said sleeve being adjacent the lower side of the table, a body mounted in the sleeve for reciprocating movements, electric means for periodically lifting and releasing said body whereby the table is vibrated by the impact of the body, and means for elevating said piston or ram 10 and the table carried thereby to an upper position independently of or simultaneous with the movements of said vibrating body.

9. In molding apparatus of the character described, a base, a cylinder extending upwardly from the base, a piston mounted in the cylinder, a table carried at the upper end of the piston on which a pattern and a flask around the pattern may be carried, a squeezing head located above the flask, a vibrating body mounted in the piston for vertical reciprocating movements whereby its impact against the ends of the piston at the ends of its movements vibrates the table and condenses the sand in the lower part of the flask, electric means for reciprocating said vibrating body, and means for carrying compressed air into the lower end of the cylinder to thereby elevate said piston and flask to the squeezing head to thereby squeeze and compress the sand in the upper part of said flask, substantially as described.

10. A construction containing the elements in combination defined in claim 9 combined with means for controlling the passage of compressed air to said cylinder and for exhausting said compressed air from the cylinder, and a conduit leading to said piston through which the exhaust air passes to circulate the exhaust air around the electric means operating said vibrating body, to thereby cool the same, substantially as described.

11. In molding apparatus of the class described, a support, a table on which a pattern and flask may be carried located at the upper end of the support, a sleeve positioned vertically below the table, a body mounted to traverse the sleeve, upper and lower solenoid windings around the sleeve, means for alternately energizing said windings, and means for automatically stopping the energizing of said windings after a predetermined number of reciprocations of the body caused by the alternate energizing of said windings, substantially as described.

12. In a molding apparatus, a vertical support, a table located at the upper end of the support, a vertical sleeve carried by the support directly under the table, a body mounted in the sleeve adapted to reciprocate therein, upper and lower solenoid windings around the sleeve, means including electric

circuits for alternately energizing the solenoids, said circuits having a manually operable switch therein normally held in open 65 position and adapted to be closed to start the apparatus in operation, mechanism including a spring actuated switch normally adapted to close the circuits when free to do so, means for operating said mechanism to 70 free said switch for closing immediately after the manually operable switch is closed, said mechanism being operated once with the energizing of both solenoid windings, and means included in said mechanism to 75 engage with said spring actuated switch to automatically move the same to inoperative position on completion of a predetermined cycle of energizings of said solenoid windings, substantially as described.

13. In a molding apparatus, a vertical support, a table located at the upper end of the support, a vertical sleeve carried by the support directly under the table, a body mounted in the sleeve adapted to reciprocate therein, upper and lower solenoid windings around the sleeve adapted when energized to attract said body and cause its reciprocation in the sleeve, electric circuits including a single feed wire connected with each of the solenoid windings and two return wires leading respectively from said windings, a commutator adapted to alternately make the circuit through said return wires, said commutator including a rotatable drum and two spaced apart half-bands on the drum, brushes connected to each of the return wires adapted to bear against the drum and against said bands, one brush bearing against a band at a time, two additional brushes bearing against the drum and connected with the ground wire of the circuits, and a switch disposed in a break in said feed wire for manually closing said circuit, substantially as described.

14. A construction containing the elements in combination defined in claim 13 combined with a support, a contact mounted on said support, a spring actuated lever pivotally mounted on the support, a contact therein 110 adapted to engage with the first named contact when the lever is free to move, a ratchet wheel mounted on the support, a pin extending from the ratchet wheel adapted in one position to engage with the lever and separate said contacts, wires connecting the contacts with the feed wire at points one each side of the manually operable switch, and means for rotating said ratchet wheel one step with each complete reciprocatory movement of the body mounted in the sleeve, substantially as described.

In testimony whereof I affix my signature.
DONALD J. CAMPBELL.
